UNITED STATES PATENT OFFICE.

HENRY B. OATLEY, OF SCHENECTADY, NEW YORK, ASSIGNOR TO AMERICAN LOCOMOTIVE COMPANY, OF NEW YORK, N. Y., A CORPORATION OF NEW YORK.

SUPERHEATER.

No. 902,440.

Specification of Letters Patent.

Patented Oct. 27, 1908

Application filed May 27, 1908. Serial No. 435,186.

To all whom it may concern:

Be it known that I, HENRY B. OATLEY, of Schenectady, in the county of Schenectady and State of New York, have invented a certain new and useful Improvement in Steam-Boiler Superheaters, of which improvement the following is a specification.

My present invention relates to superheaters of the so-called "smoke box" type, which is to say; of the general class or type in which the superheating appliances are located in the smoke box of a fire tube steam boiler, and its object is to provide a superheater of such type which shall be readily applicable in a smoke box of the ordinary form and dimensions; in which as large an amount of superheating surface as practicable may be presented without enlargement of the smoke box, interference with the draft, or prevention of access to the boiler tubes; and in which the superheating pipes shall be so disposed and connected as to be conveniently accessible for purposes of renewal or repair, and be exempt from liability to injury under expansion and contraction.

The improvement claimed is hereinafter fully set forth.

In the accompanying drawings: Figure 1 is a vertical longitudinal central section through the forward portion of a locomotive boiler, illustrating an application of my invention; Fig. 2, a horizontal section through the same, with the T head also shown in section; Fig. 3, a view, partly in front elevation, with the smoke box front removed, and partly in vertical transverse section, on the line *a-a* of Fig. 2; Fig. 4, a vertical longitudinal section illustrating an application of my invention in a compound locomotive; Fig. 5, a horizontal section of the construction shown in Fig. 4, and; Fig. 6, a vertical transverse section, on the line *b-b* of Fig. 4.

Referring first to Figs. 1 to 3 inclusive, my invention is herein set forth as applied in a locomotive boiler, 4, which is substantially of the ordinary construction, and is provided, at its forward end, with a smoke box, 4^a, of the ordinary form and dimensions. A plurality of fire tubes, 4^b, extend from the firebox at the rear end of the boiler, which is not shown, to the front flue sheet, 4^c, and the products of combustion pass through said tubes to the

smoke box, 4^a, from which they are discharged, through the stack, in the usual manner. Steam is supplied from the boiler to 55 the cylinders of the locomotive, through a main steam pipe or dry pipe, 61, passing through the front flue sheet, and connected, in front thereof, to a T head, 62, from which it is conducted through superheater pipes, 69, 60 which, with their accessories, will be presently described, and, after being superheated in said pipes, passes to the cylinders through delivery steam pipes, 63, located on opposite sides of the smoke box, in the lower portion 65 thereof.

A casing or header, 70, is located on each side of the smoke box, adjoining, as closely as practicable, the front ring, 4^b, thereof, each of said headers comprising a saturated steam compartment, 70^e, and a superheated steam compartment, 70^f, which are of substantially rectangular transverse section, and are, preferably, as shown, formed integral and connected by an intermediate plate or 75 web. The headers are curved vertically, so as to conform, as nearly as may be, with the curvature of the smoke box wall, and to stand as closely thereto as practicable and leave the maximum open space between 80 them which is available under the diameter of the smoke box. They are supported on rods, 70^r, connected to the bottom of the smoke box, and are connected at the top by a transverse rod, 70^s, passing through lugs 85 on the fronts of the headers and provided with adjusting nuts engaging screw threads on its ends.

By reference to Figs. 2 and 3, it will be seen that the walls of the saturated and superheated steam compartments of the headers are substantially completely separated, and therefore that there will be no loss of heat by its transfer through said walls from the superheated to the saturated steam. 95

While, as a matter of convenience in manufacture and installation, the saturated and superheated steam compartments of each of the headers are preferably cast integral, as shown, it will be obvious that they may, if 100 deemed advisable by the constructor, be made in separate castings, without departure from the spirit and operative principle of my invention.

Laterally and forwardly extending branch steam supply pipes, 62^b, are formed upon or secured to the T head, 62, each of said pipes being connected, at its forward end, to a nozzle or short pipe, 70^a, extending rearwardly from the upper portion of the saturated steam compartment, 70^e, of one of the headers, and nozzles, 70^b, on the lower portions of the superheated steam compartments, 70^f, of the headers are connected to branch or delivery steam pipes, 63, leading to the engine cylinders.

The saturated steam compartment, 70^e, of each of the headers, is connected with the superheated steam compartment, 70^f, thereof, by a plurality of loops or bends of superheater pipes, 69, each of which extends rearwardly from one of the saturated steam compartments, as nearly to the front flue sheet, 4^d, as may be practicable, and is bent alternately forwardly and rearwardly into a plurality of substantially horizontal convolutions, as clearly shown in Fig. 2, and connected, at its forward end, to the adjacent superheated steam compartment, 70^f. In addition to the advantage of presenting a very large area of superheating surface, located in such position as to be directly exposed to the heat of the products of combustion passing through the smoke box, from the boiler tubes to the stack, the convoluted form of the superheater pipes enables the action of expansion and contraction in the pipes to be fully compensated, and liability to leakage at their connections with the headers to be correspondingly reduced. Openings, which are closed by removable plugs, 70^c, are formed in the fronts of the headers, said openings providing for the insertion, examination, and repair of the superheater pipes. In the event of leakage at the joints, the plugs can be detached and the superheater pipes expanded as required, and it will be seen that they are much more readily and conveniently accessible than in superheaters in which the headers are located adjacent to the front flue sheet. In order to prevent loss of heat of the smoke box gases, and enable its action to be exerted as effectively as possible upon the superheater pipes and headers, the smoke box front, 4^h, is preferably made double, with an inclosed lagging of suitable non-conducting material.

The smoke box is, where solid fuel is used, fitted with a spark arresting appliance of any suitable and preferred construction, which is, in this instance, shown as comprising an ordinary diaphragm or deflecting plate, 4^e, extending from the front flue sheet, 4^d, to the front of the exhaust pipe, 64, below the nozzle of the latter, and lateral and longitudinal sheets of netting or perforated plate, 4^f. In order to direct the escaping gases towards the superheater pipes, as well as to prevent the access of sparks to the stack

except through the openings of the netting or perforated plate; a longitudinal partition plate, 4^g, extends forwardly from the deflecting plate, 4^e, to the netting or perforated plate, on the inner side of each of the sets of superheater pipes, said plates causing the gases to pass forwardly and upwardly to the stack around the superheater pipes.

In operation, saturated steam from the boiler passes through the dry pipe, 61, T head, 62, and branch steam supply pipes, 62^b, into the saturated steam compartments, 70^e, of the headers, and thence, through the convolutions of the sets of superheater pipes, 69, into the superheated steam compartments, 70^f, being, in its traverse through the headers and superheater pipes, thoroughly superheated by the hot products of combustion which pass through the smoke box. The superheated steam passes from the superheated steam compartments into the communicating branch or delivery steam pipes, 63, and thence to the engine cylinders for utilization therein.

Figs. 4, 5, and 6 illustrate the application of a superheater embodying all the essential features of that above described, for the purpose of superheating the high pressure exhaust steam of a compound locomotive, during its traverse from the high pressure to the low pressure cylinder thereof, steam being supplied to the high pressure cylinder from the dry pipe, 61, and T head, 62, by a branch steam supply pipe, 62^b, in the ordinary manner. The headers, 70, are, in this case, similarly located to those first described, and are of the same general form, each being divided into a saturated steam compartment, 70^e, and a superheated steam compartment, 70^f, the walls of which are separated by intervening spaces. The saturated steam compartments communicate, at their lower ends, by a supply nozzle, 70^a, with a section, 62^c, of the exhaust pipe leading from the high pressure cylinder, and communicate, one with the other, by an upper transverse passage, 70^d. The superheated steam compartments communicate, one with the other, at their lower ends, through a transverse passage, 70^e, below which they communicate, in common, with the steam passages leading to the low pressure cylinder, through a delivery nozzle, 70^b. The saturated and superheated steam compartments are, similarly to those first described, connected by a plurality of loops or bends of superheater pipes, 69, the convolutions of which provide passages having a large area of superheating surface, interposed in the line of traverse of the high pressure exhaust steam from the high pressure to the low pressure cylinder, and in which it is superheated as before described.

It will be seen that the application of my invention does not involve any change of form or dimensions in smoke boxes of the

present standard type, nor any substantial modification of the accessories thereof now in general use. As large an area of superheating surface as is obtainable under these conditions is afforded, and the joints are located as far as possible from the front flue sheet and in position where they are readily accessible when required. The projection of the headers towards the vertical central plane of the smoke box is, by reason of their vertically curbed form, not substantially greater than that of the present branch steam pipes, and the objection of interference with access to the boiler tubes, which has obtained, to a greater or less degree, in prior constructions, is therefore correspondingly minimized.

I claim as my invention and desire to secure by Letters Patent:

1. The combination, with a steam boiler, of a vertical header or casing, supported in the smoke box adjacent to the front and the side thereof, and comprising separate saturated and superheated steam compartments, a plurality of loops or bends of superheater pipes, connected, at their opposite ends, to the saturated and the superheated steam compartments, respectively, and extending rearwardly therefrom, a steam supply connection opening into the saturated steam compartment, and a steam delivery connection leading out of the superheated steam compartment.

2. The combination, with a steam boiler, of a vertical header or casing, supported in the smoke box adjacent to the front and the side thereof, and having its outer wall curved in general accordance with the wall of the smoke box, said header comprising separate saturated and superheated steam compartments, a plurality of loops or bends of superheater pipes, connected, at their opposite ends, to the saturated and the superheated steam compartments, respectively, and extending rearwardly therefrom, a steam supply connection opening into the saturated steam compartment, and a steam delivery connection leading out of the superheated steam compartment.

3. The combination, with a steam boiler, of a vertical header or casing, supported in the smoke box adjacent to the front and the side thereof, and comprising separate saturated and superheated steam compartments, a plurality of loops or bends of superheater pipes, each extending in alternate rearward and forward convolutions, and connected, at its opposite ends, to the saturated and the superheated steam compartments, respectively, a steam supply connection opening into the saturated steam compartment, and a steam delivery connection leading out of the superheated steam compartment.

4. The combination, with a steam boiler,

of a vertical header or casing, supported in the smoke box adjacent to the front and the side thereof, and comprising separate saturated and superheated steam compartments, a plurality of loops or bends of superheater pipes, connected, at their opposite ends, to the saturated and the superheated steam compartments, respectively, and extending rearwardly therefrom, a steam supply connection opening into the saturated steam compartment, a steam delivery connection leading out of the superheated steam compartment, and a vertical partition plate extending longitudinally in the smoke box, on the inner side of the set of superheater pipes.

5. The combination, with a steam boiler, of a T head, branch steam supply pipes extending forwardly therefrom, a pair of vertical headers or casings, each supported in the smoke box adjacent to the front and one side thereof and comprising a saturated steam compartment connected to one of the branch steam supply pipes and a separate superheated steam compartment, a plurality of loops or bends of superheater pipes, each connected, at its opposite ends, to the saturated and superheated steam compartments, respectively, of one of the headers, and extending rearwardly therefrom, and branch steam delivery pipes each connected to the superheated steam compartment of one of the headers.

6. The combination, with a steam boiler, of two vertical headers or casings, each supported in the smoke box adjacent to the front and one side thereof, and comprising separate saturated and superheated steam compartments, a plurality of loops or bends of superheater pipes, each connected, at its opposite ends, to the saturated and the superheated steam compartment, respectively, of one of the headers, and extending rearwardly therefrom, steam supply connections opening into the saturated steam compartments, steam delivery connections leading out of the superheated steam compartments, a deflecting plate or diaphragm extending transversely in the smoke box forward of the front flue sheet, a foraminous sheet or plate extending transversely forward of the deflecting plate and between the superheater pipes, and vertical partition plates extending forwardly from the deflecting plate and connected to the foraminous sheet or plate.

7. The combination, with a steam boiler, of two vertical headers or casings, each supported in the smoke box adjacent to the front and one side thereof and comprising separate saturated and superheated steam compartments, a passage connecting the saturated steam compartments of the two headers, a passage connecting the superheated steam compartments of the two headers, a

plurality of loops or bends of superheater pipes, each connected, at its opposite ends, to the saturated and the superheated steam compartment, respectively, of one of the headers, and extending rearwardly therefrom, a steam supply connection leading into the saturated steam compartment of one of

the headers, and a steam delivery connection leading out of the superheated steam compartment of the other header.
